CLAIM

The ornamental design for a shaft sleeve puller, as shown and described.

DESCRIPTION

FIG. 1 is an exploded front elevational view of the shaft sleeve puller showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an isometric view thereof; and,

FIG. 8 is an isometric view thereof, with the cylindrical element assembled.
